UNITED STATES PATENT OFFICE.

JOHN W. FORSYTHE, OF WILKINSBURG, PENNSYLVANIA.

DUMPING BUCKET.

Application filed February 23, 1922. Serial No. 538,615.

To all whom it may concern:

Be it known that I, JOHN W. FORSYTHE, a citizen of the United States, and resident of Wilkinsburg, in the county of Allegheny and State of Pennsylvania, have invented certain new and useful Improvements in Dumping Buckets, of which the following is a specification.

This invention relates to dumping buckets and more particularly to self-dumping buckets, and has for its object the provision of a bucket of this class that will be free of springs or other fragile parts that are liable to become broken or damaged.

Another object is to provide a bucket that may be dumped and righted by the operation of the hoisting mechanism with which it is employed without the necessity of any manual labor.

A further object is to so construct the bucket that when in use in a car or other similar location it will be so spaced from the sides thereof that the bail will be free to operate.

A still further object is to provide a bucket having the novel construction and combination of parts hereinafter described in detail and illustrated in the accompanying drawings, in which—

Figure 1 is a side elevation of my bucket in its vertical position in full lines, and in its rearwardly inclined position ready for dumping in dotted lines.

Figure 2 is a side elevation of the bucket in dumping position.

Figure 3 is a rear elevation.

Figure 4 is a top plan view.

Figures 5 and 6 are side elevations of the lower ends of the side portions of slightly modified forms of bails adapted for use with my invention.

Referring more particularly to the drawings, the numeral 2 designates the bucket body as a whole which has vertical side and rear walls and an upwardly and outwardly inclined front wall. A trunnion block 3 having trunnions 4 is secured adjacent the lower edge of each side wall, and the forward edge of the blocks 3 extend outwardly forming bracket members 5 for a purpose to be described.

A bail member 6 having the usual hook engaging eye 7 at the center of its top bar and having vertically disposed side portions 8 which are provided with elongated slots 9 and journaled on said trunnions, the

slots 9 providing for reciprocatory movement of the bail relative to the trunnions.

A supporting bracket 10 is secured to each side of the bucket below the trunnion block 3 and has its upper end apertured and fitted over the trunnion 4 so as to support the outer end thereof.

The side portions 8 of the bail are provided with projections or catches 11 adapted to be inserted between stop members 12 and 13 on the sides of the bucket when the bail is in its uppermost vertical position, and thus prevent tilting of the bail.

The stop member 12 projects outwardly from the side of the bucket an appreciable distance beyond the bail so as to space the bucket a sufficient distance from the side of the car or other such obstruction to prevent any interference with the free operation of the bail.

The stop member 13 is provided with a rearwardly and upwardly inclined lower face 14 adapted to form a skid or slide bearing against which the upper face of the catch 11 on the bail will bear when operating to tilt or dump the bucket.

The side portions 8 of the bail are provided with a short integral lever arm 15 adapted to engage the bracket member 5 on the trunnion block when the bail is permitted to move downwardly by gravity, thereby tilting or throwing the bail rearwardly so as to engage the upper face of the member 11 with the lower inclined face 14 of the member 13.

A stop member 16 is secured to each side of the bucket and projects an appreciable distance outwardly therefrom. The member 16 is adapted to strike the bail when the bucket is tilted or dumped and thus limit its movement; it also serves as a rest for the bail when the bail is lowered during the loading of the bucket; it also co-operates with the stop member 12, and aids in spacing the bucket away from the sides of a car or other obstruction.

In Figure 5 I have shown a modified construction for the lower end of the side portions 8 of the bail. In this construction the elongated slot 9 through which the trunnion 4 is adapted to project is substantially the same as in the preferred form. However, instead of the lever arm 15 on the preferred form, a downwardly projecting toe member 15^a is provided which is adapted to engage a projection 15^b which pro-

jects from the side wall of the bucket at a point below and slightly forward of the trunnion 4. The operation of this form of bail is substantially the same as the preferred form.

In Figure 6 I have shown a still further modified construction for the lower end of the side portions 8 of the bail. In this construction the lower end of the bail is enlarged to form a forwardly projecting portion 8^a and an elongated slot 9^a is formed in the portion 8^a to receive the trunnion 4. It will be noted that the lever 15 is omitted from this form of bail. However, the bail will automatically tilt rearwardly when the lifting pull is released and the crane hook is slackened. That is, as the lifting pull is released the bail will drop by gravity until the top of the slot 9^a engages the trunnion 4, then, due to the slot being in advance of the vertical axis of the bail, the bail will be overbalanced and will tilt rearwardly.

In order to more clearly describe the novel features of this bucket, a detailed operation is given. Assuming that the bucket is resting on the ground, loaded, and the bail 6 is in a horizontal position resting on the stop members 16, the operation will be as follows—

30 A crane hook or other lifting member will be secured to eye 7 of the bail and the lifting pull started so as to rotate the bail about the trunnions 4 and raise it. As the bail is raised, the upper faces of the catches 11 will engage the inclined underside 14 of the stop member 13 and force the bail downwardly until the catches 11 clear the stops 13 at which time the bail will be in a vertical position and any further lifting pull of the 35 crane hook will lift the bail vertically relative to the trunnions and insert the catches 11 between the stops 12 and 13. The bail will continue to lift until the bottom of the slots 9 engage the trunnions, when the bucket 40 will be lifted.

When it is desired to dump the bucket 2 it is again rested on the ground and the lifting pull released so as to slacken the crane hook. As the crane hook slackens the bail 45 6 will drop by gravity until the catches 11 are free of the stops 12 and 13, and the short lever arms 15 will engage the bracket members 5 on the trunnion blocks, thus tilting or throwing the bail rearwardly so that the 50 catches 11 will engage the lower inclined face 14 of the stop members 13. A lifting pull will then again be applied to the crane hook which will tend to pull the bail upwardly. However, the bail in its tilted position is locked between the brackets 5 and 55 stop 13 and is forced to slide along the inclined face 14 of the stop 13 until the bottom of the slots 9 engage the trunnions 4. A continued lifting pull of the crane hook 60 65 will then cause the bucket to lift, and due

to the rearwardly inclined position of the bail, the bucket will be overbalanced and therefore will tilt forwardly to dump or discharge its load.

After the load has been dumped from the 70 bucket, the bucket will be returned for a new load and again rested on the ground or other firm base, and the bail will be allowed to rest upon the stop members 16 in which position the above cycle of operations was 75 started.

While I have shown and described only one preferred form of my improved apparatus, various changes in construction and combination of parts may be made without 80 departing from the spirit of my invention as defined in the appended claims.

I claim—

1. A self-dumping bucket comprising, a 85 bucket body, a bail pivotally mounted thereon, means for locking said bail in a vertical position with relation to said bucket body, said bail being adapted to be automatically released and inclined rearwardly when the lifting pull is removed therefrom, and said bail being adapted to dump said bucket when lifting pull is again applied thereto.

2. A self-dumping bucket comprising, a 90 bucket body, trunnions projecting outwardly from the sides of said bucket, a bail having 95 recessed vertical side portions which engage said trunnions, said bail being adapted to move downwardly relative to said trunnions when the lifting pull is removed therefrom, and means for tilting said bail rearwardly 100 during its downward movement so as to cause said bucket to dump when the lifting pull is again applied to said bail.

3. A self-dumping bucket comprising, a 105 bucket body, trunnions projecting outwardly from the sides of said bucket, a bail having recessed vertical side portions which engage 110 said trunnions, a pair of locking members on each side of said bucket, the rearmost of said locking members having its lower face inclined upwardly and rearwardly, said bail 115 being adapted to reciprocate vertically on said trunnions, a catch on the inner face of each side portion of said bail adapted to be engaged between said locking members, means for tilting said bail rearwardly when the lifting pull is released therefrom and it is allowed to move downwardly by gravity relative to said trunnions so as to dump said 120 bucket when lifting pull is again applied to said bail.

4. A self-dumping bucket comprising, a 125 bucket body, trunnions projecting outwardly from the sides of said bucket, a bail having recessed vertical side portions which engage 130 said trunnions, a pair of locking members on each side of said bucket, the rearmost of said locking members having its lower face inclined upwardly and rearwardly, said bail being adapted to reciprocate vertically on

- said trunnions, a catch on the inner face of each side portion of said bail adapted to be engaged between said locking members, said bail being adapted to move downwardly by gravity when the lifting pull is removed therefrom so as to release said catches from said locking members, bracket members projecting from the side of the bucket adjacent said trunnions, short lever arms formed integral with and adjacent the lower end of the side portions of said bail, said lever arms being adapted to strike said brackets during the downward movement of said bail to rock said bail rearwardly so as to engage the catches on the side portions of the bail with the inclined lower face of said rearmost locking members, whereby said bail will be forced to rotate on said trunnions and move rearwardly when lifting pull is again applied to said bail, thereby dumping said bucket.
5. A self-dumping bucket comprising, a bucket body, trunnions projecting outwardly from the sides of said bucket, a bail having recessed vertical side portions which engage said trunnions, a pair of locking members on each side of said bucket, the rearmost of said locking members having its lower face inclined upwardly and rearwardly, said bail being adapted to reciprocate vertically on said trunnions, a catch on the inner face of each side portion of said bail adapted to be engaged between said locking members, said bail being adapted to move downwardly by gravity when the lifting pull is removed therefrom so as to release said catches from said locking members, bracket members projecting from the side of the bucket adjacent said trunnions, short lever arms formed integral with and adjacent the lower end of the side portions of said bail, said lever arms being adapted to strike said brackets during the downward movement of said bail to rock said bail rearwardly so as to engage the catches on the side portions of the bail with the inclined lower face of said rearmost locking members, whereby said bail will be forced to rotate on said trunnions and move rearwardly when lifting pull is again applied to said bail, thereby dumping said bucket, said bail being adapted to have said catches automatically inserted between said locking members to again lock said bail in a vertical position by again removing the lifting pull from said bail and then applying a lifting pull to said bail to rotate it around said trunnions to a vertical position and raising said bail until said catches are in locked position between said locking members.
- 10 15 20 25 30 35 40 45 50
- have said catches automatically inserted between said locking members to again lock said bail in a vertical position by again removing the lifting pull from said bail and then applying a lifting pull to said bail to rotate it around said trunnions to a vertical position and raising said bail until said catches are in locked position between said locking members.
- 55 60 65 70 75 80 85 90 95 100
6. A self-dumping bucket comprising, a bucket body, trunnions projecting outwardly from the sides of said bucket, a bail having recessed vertical side portions which engage said trunnions, a pair of locking members on each side of said bucket, the rearmost of said locking members having its lower face inclined upwardly and rearwardly, said bail being adapted to reciprocate vertically on said trunnions, a catch on the inner face of each side portion of said bail adapted to be engaged between said locking members, said bail being adapted to move downwardly by gravity when the lifting pull is removed therefrom so as to release said catches from said locking members, bracket members projecting from the side of the bucket adjacent said trunnions, short lever arms formed integral with and adjacent the lower end of the side portions of said bail, said lever arms being adapted to strike said brackets during the downward movement of said bail to rock said bail rearwardly so as to engage the catches on the side portions of the bail with the inclined lower face of said rearmost locking members, whereby said bail will be forced to rotate on said trunnions and move rearwardly when lifting pull is again applied to said bail, thereby dumping said bucket, said bail being adapted to have said catches automatically inserted between said locking members to again lock said bail in a vertical position by again removing the lifting pull from said bail and then applying a lifting pull to said bail to rotate it around said trunnions to a vertical position and raising said bail until said catches are in locked position between said locking members.
- 70 75 80 85 90 95
- In testimony whereof, I have hereunto set my hand.
- JOHN W. FORSYTHE.
